UNITED STATES PATENT OFFICE.

SIMON KLEIN, OF BERLIN, GERMANY, ASSIGNOR TO GENERAL ELECTRIC COMPANY, A CORPORATION OF NEW YORK.

DEVICE ADAPTED TO SHOW WHETHER AN ELECTRIC INCANDESCENT LAMP HAS BEEN IN USE.

1,077,479.

Specification of Letters Patent.

Patented Nov. 4, 1913.

Application filed March 17, 1910, Serial No. 550,059. Renewed May 1, 1913. Serial No. 764,936.

To all whom it may concern:

Be it known that I, SIMON KLEIN, engineer-chemist, a citizen of Germany, residing at No. 126 Müllerstrasse, in the city of Berlin, German Empire, have invented a new and useful Device Adapted to Show Whether an Electric Incandescent Lamp Has Been in Use; and I do hereby declare the following to be a full, clear, and exact 10 description of the same.

The invention relates to an attachment for electric incandescent lamps, adapted to show whether such a lamp has been used, and to enable the time of its use to be controlled.

15 It is universally known that lamps having metal filaments are relatively very expensive and easily broken. For this reason, it is usual for the manufacturer to replace such lamps as become defective during the transport or when first put into use. Heretofore, only a very long use could be ascertained by examining the condition of the filament, and it frequently happens that the purchaser claims new lamps for those which 20 have been in use for a considerable time.

25 For manufacturers of electric incandescent lamps, it is, therefore, of great importance to provide means which will clearly show whether a lamp has been put into use.

30 According to my invention, I provide such a device, which, when the circuit of the lamp is closed, that is, when the lamp is burning, is so modified by physical, chemical or other action, that the fact of the lamp 35 having been used can be discerned. For this purpose, any light sensitive color may be used. I may use a paper which has been rendered sensitive to light, or I may employ cotton or felt steeped in such light sensitive 40 coloring material. This light sensitized material is introduced into the seal of the lamp in the hollow space left in the process of manufacturing the lamp. For photographic purposes there are manufactured a 45 number of light sensitive colors, and these may be used with greater or less success. I have used with complete success a color material which is sold in the trade under the name "Tosulrot." I am unable to give the 50 chemical composition of this material, as it is kept by the manufacturers as a trade secret.

In the accompanying drawings, I illustrate one manner of using my invention.

Figure 1 shows, in elevation, a metal filament lamp; Fig. 2 is a fragment, showing a longitudinal section through the glass seal or base; and Fig. 3 is a cross-section, on the line A—B, of Fig. 2.

The lamp shown in Fig. 1 is constructed 60 in the well-known manner, and comprises a small glass tube or base *a* having an outwardly-flaring flange *b*, which is molten on to or fused to the lower end of the bulb *d*. Conductors *g*, *g*, pass through the upper 65 flattened and compressed end *e*, of the seal *a*, and that end supports a carrier, *f*, of glass, for the filaments, *k*. Within the hollow space, *h*, of base, *a*, there is a material, *i*, for example, wool or felt steeped in a material such as tosulrot which, under the action 70 of light from the filaments *k* changes its color or tint.

I have found it to be of special advantage 75 to provide some substance of a color sensitive to light in the glass foot of the incandescent lamp, and the dye used should preferably be of a character adapted to the special physical and chemical properties of the light emitted by a metal filament. Under the influence of the light of the lamp, the dye will pass through various stages, showing the time the lamp has been in use. The provision of such a sensitive substance in the foot of a lamp is of special advantage, because at this place it is protected 80 more or less against day-light, and, moreover, the day-light must pass through the wall of *a* and also through the wall of *d*, before it arrives at the dyed substance, while 85 the lamp light, which moreover is richer in ultra violet rays, has only to pass through one thickness, that of *a*. Moreover, the color with which material *i* is steeped is so chosen that it is less sensitive to daylight than to 90 the light emitted from the incandescent metallic filament. The fading or change in 95 the color of the substance, as experiments have shown, will enable the time the lamp has been used to be ascertained. For the 100 purpose last mentioned, it is of advantage to provide several materials of different colors or of colors having different degrees of sensitiveness, which, according to the

time the light has acted on the same, pass through various stages.

It should be mentioned that this device can be adopted not only to show whether incandescent lamps have been in use, for which purpose however it is of great importance, but also for other apparatus, in which the electric current produces light.

What I claim and desire to secure by Letters Patent of the United States is:

1. The combination, with an incandescent lamp, of a device sealed thereto and adapted to show whether said lamp has been used, substantially as set forth.
- 15 2. The combination, with an incandescent lamp, of a substance sensitive to light and adapted, by changing its appearance under the influence of light, to show when said lamp has been used, substantially as set forth.
- 20 3. The combination, with an incandescent lamp, of a body dyed in a color sensitive to light, substantially as and for the purpose set forth.
- 25 4. The combination, with an incandescent

lamp, of a porous substance dyed in a color sensitive to light, substantially as and for the purpose set forth.

5. The combination, with an incandescent lamp, of a body sensitive to light and provided in the foot of said lamp, substantially as and for the purpose set forth.

6. An article of manufacture comprising an incandescent lamp and means permanently attached thereto and adapted to be affected by the influence of the light of the lamp to show whether the lamp has been used.

7. An article of manufacture comprising, an incandescent lamp having a base tube, a substance sensitive to light in said tube, and a lamp socket sealing said tube.

In testimony whereof, I have signed my name to this specification in the presence of two subscribing witnesses.

SIMON KLEIN.
